UNITED STATES PATENT OFFICE.

SAMUEL WILLIAM TURNER, OF LONDON, ENGLAND, ASSIGNOR TO THE
YOST TYPEWRITER COMPANY, LIMITED, OF LONDON, ENGLAND.

INKING APPLIANCE FOR TYPE-WRITERS.

SPECIFICATION forming part of Letters Patent No. 728,050, dated May 12, 1903.

Application filed April 29, 1901. Serial No. 57,862. (No model.)

To all whom it may concern:

Be it known that I, SAMUEL WILLIAM TURNER, a subject of the King of Great Britain and Ireland, residing at 68 Park Lane, Clis-
5 sold Park, London, England, have invented certain new and useful Improvements in Ink-
ing Appliances for Type-Writers, of which the following is a specification.

This invention relates to inking devices
10 more particularly applicable to type-writers
of the kind wherein a pad is employed for
inking the type; and it consists in providing
means whereby the printing may be per-
formed in various colors, the efficiency of the
15 machine being thereby increased.

In the accompanying drawings, Figure 1 is a plan view of an inking device constructed according to my invention, Fig. 2 being a view looking at the left-hand end and Fig. 20 3 a view looking at the right-hand end of Fig. 1. Fig. 4 is a diagrammatic view showing the application of the improved device to a Yost type-writer. Fig. 5 is a view of the coupling employed for driving the inking device from the mainspring and drum which works the carriage. Fig. 6 is an elevation of the device as seen from the left in Fig. 2 and from above in Fig. 1, the spool C and its bevel-wheel D being omitted, so as to disclose
25 the main body of the frame.

In carrying out my invention as applied, by way of example, to a Yost type-writer, wherein the type-levers are arranged radially within a ring R, Fig. 4, which contains the
35 inking-pad, and are capable of bringing the type successively to the printing-point at or about the center of the said ring, the device comprises a frame or carrier A, adapted for attachment to the plate P of the main ring.
40 In the example shown the frame is formed with two slots a a, which engage two clamping-screws (not shown) with which the plate of the main ring is provided. Loosely mounted upon a sleeve or bearing A², formed at
45 one extremity of the carrier A, is a spindle B, constructed to be moved longitudinally in a manner hereinafter described. Upon this spindle B is loosely mounted a pair of spools C C, the latter being driven by bevel-wheels
50 D D, attached thereto and capable of sever-ally meshing with the bevel-wheel D', the lat-

ter being coupled with the spindle pertaining to the mainspring and drum, which actuates the carriage of the machine by means of the coupling d. (Shown detached in Fig. 5.) An 55 arm d' on a plate d^X, attached to the ratchet-wheel d² by means of pin d¹⁰, engages a slot d^X, formed in the coupling d and by means of a spring-pressed pawl d³ imparts motion to the bevel-wheel D', which is mounted to 60 rotate freely on a stud D⁰, screwed into the back of the sleeve or bearing A². The direction of motion of the spools may be reversed by means of the lever E, which is pivoted at e in the frame A and engages with a pin e', 65 attached to the spindle B, the pin passing through a slot (shown in dotted lines) in the sleeve or bearing A². By moving the free end of the lever E to the one side or the other the spindle B is moved longitudinally in its bearing A² by means of the pin e', which is in engagement with the lever, thus rendering the one spool or the other the driven spool, or both spools may be rendered inoperative by allowing the lever to assume the mid position, as 70 shown in the drawings. The rotation of the gearing during a certain movement of the carriage—in other words, during the return movement—may be prevented by means of the pawl F, which may engage with the teeth 75 of the bevel-wheel D', the latter serving the purpose of a ratchet-wheel. The bevel-wheel D' is thus held stationary, while the ratchet-wheel d² rotates freely against the pawl d³. The ribbon G extends above and to a little dis- 85 tance beyond the printing-point G', Fig. 6. From the one spool it is led and supported by an arm A', which extends across the machine between the main ring R and the carriage K, the ribbon being then led back to the other 90 spool. Guide-rollers may be provided on the arm, with a view to assisting the travel of the ribbon. One of such guide-rollers is shown at a'. The arm A' is preferably formed in two or more parts hinged or pivoted together, 95 as shown at A^X, in order to admit of the outer or hinged portion being folded back, as indicated in broken lines in Fig. 1, thus permitting the ribbon being moved away from the printing-point when occasion requires. The 100 outer portion of the arm A' is supported on the rollers a' when the apparatus is extended

across the machine. The spools may be made removable from the spindle B by providing the bevel-wheels D D with sleeves d^o d^o and connecting the spools with the wheels by 5 means of pins d^o . The set-screws $b b$ secure the spools in position upon the spindle B. By these means spools containing inking-ribbons of different colors may be readily exchanged.

10 The herein-described attachment may be employed either in conjunction with or independently of the ordinary inking-pad.

What I claim as my invention, and desire to secure by Letters Patent, is—

15 1. In a type-writer inking device operated by the mainspring and drum which actuates the carriage, a carrier having a jointed arm serving to support the inking-ribbon and to guide the same to and from the printing-point, 20 the carrier being capable of folding back on

itself, whereby the inking-ribbon remains taut and is moved away from the printing position, substantially as set forth.

2. In an inking device for type-writers, the combination with the carrier, of the spindle 25 mounted rotatively therein, the bevel-wheels D, D, rotatable on said spindle, the bevel-wheel D', rotatable on the carrier, means for putting either of the wheels D into gear with the wheel D', and the spring-pawl F adapted 30 to engage the teeth of the gear-wheel D', substantially as set forth.

In testimony whereof I have signed my name to this specification in the presence of two subscribing witnesses.

SAMUEL WILLIAM TURNER.
